UNITED STATES PATENT OFFICE

LOUIS C. EDGAR, OF SWISSVALE, PENNSYLVANIA

REGENERATIVE FURNACE

Application filed July 8, 1930. Serial No. 466,515.

This invention relates broadly to regenerative furnaces and more particularly to regenerators for use with open hearth steel furnaces.

Unidirectional combustion in open hearth furnaces and flow of hot gases and air to be heated in the regenerators is known to possess considerable merit, and various methods of regenerator construction have been advanced 10 with this end in view, among which may be mentioned a bodily movable regenerator structure by means of which the regenerators, instead of being permanently connected with the ends of the furnace, are arranged so that they may be periodically interchanged. Such structures, however, are impracticable and, so far as known, have never been successfully applied.

The present invention contemplates the 20 provision of a particular type of furnace and regenerator structure whereby unidirectional combustion and flow of hot gases and the air to be heated may be obtained from stationary regenerators or checkers having the inlet and outlet ends thereof permanently connected to the inlet and discharge ports of the furnace.

Thus, the inlet and discharge ports are not called upon to do double duty and consequently may be designed with their particular functions in view. Likewise, the checker structure may be given a predetermined arrangement in view of the admission of the hot gases and the air to be heated always at one end of the regenerator chambers, as in the case where it is desired to use checkers having the largest openings at the point where the greatest cinderizing action occurs, or adjacent the exhaust and, in fact, the construction of the furnace as a whole may be given a predetermined design with a view toward improving its efficiency and lengthening the life of the regenerators.

The invention is illustrated as applied to 45 an open hearth steel furnace utilizing a fuel such as natural gas or tar, which does not require preheating in the checkers, the air only being preheated by the latter, which may be of any conventional design but which are herein shown as of graduated construction. It will be understood, however, that the in-

vention may be found adaptable to other types of furnaces and also that any particular grade of fuel may be utilized, such as producer gas, which may be preheated and mixed with the air from the checkers, any number 55 of which may be employed.

In the drawings:

Figure 1 is a view partly in horizontal section and partly in plan of an open hearth furnace and regenerators, the top walls of the 60 latter being broken away in part to show the checkerwork below;

Fig. 2 is a view in transverse vertical section taken on the line II—II, Fig. 1; and

Figs. 3 and 4 are sectional views taken, 65 respectively, on the lines III—III and IV—IV, Fig. 1.

The numeral 5 generally designates an open hearth furnace having the usual hearth 6 for receiving the bath of molten metal. A 70 gas, tar or like fuel inlet port or burner 7 is illustrated at one end of the furnace, and below this port is the usual air intake port 8, see Figs. 2 and 3, the heated air passing into this port from the checkers and up through 75 ports 8^a on opposite sides of the fuel inlet port 7, where it is mixed with the fuel and the flame directed across the open hearth 6.

The products of combustion pass off at the left as here shown and down through port 9 80 and out through port 9^a to the checkers, the slag pocket 10 opening into the port 9^a, note Fig. 4. It will thus be seen that the furnace is of the unidirectional combustion type, the air and gas being always admitted at one end 85 of the furnace and the products of combustion passing off at the opposite end, the inlet and outlet ports being designed with their particular functions in view.

The regenerator arrangement and construction which permits unidirectional combustion in the furnace is clearly illustrated in Fig. 1. The regenerators, which are two in number in the present instance, are generally indicated at 12 and 13, and comprise the usual 95 brick checkerwork 14, which is housed by refractory walls 15 and reinforcing buckstays 16 and tie rods 17. The regenerators are shown in the shape of a horseshoe with each end connected to the furnace. The outlet 100

port 9^a for the products of combustion divides into two entrance passages at 9^b and 9^c, each passage being controlled by any preferred type of refractory-faced reversing valve 18 and 18^a, which may be worked either manually or automatically.

It will be seen that by suitably manipulating the valves 18 and 18^a, the waste gases or products of combustion may be alternately directed into the regenerator chambers 12 and 13 as they are exhausted from the furnace.

The waste gases or products of combustion are directed into the upper part of the regenerator chamber and travel down through the checkerwork of the regenerators and into the bottom part of said chamber and then pass out to the stack flue through lower outlet passages or conduits 19 and 19^a, note Fig. 3 and dotted outlines in Fig. 1, each passage being controlled by reversing valves 20 and 20^a, the passages 19 and 19^a merging into outlet flue 21, which leads to the stack 22.

The air to be heated is alternately admitted into the regenerators at the same extremity as the hot gases, or the outlet end of the furnace, through inlet ports or conduits 23 and 23^a—which are controlled by the usual saucer valves or valves of any preferred type as at 24 and 24^a which may be controlled either manually or automatically—and passes into the bottom of the regenerator chamber and upwardly through the checker openings into the dome or top of said chamber and flows along said chamber and passes out of each regenerator through outlet passages 25 and 25^a, which are controlled by reversing valves 26 and 26^a, and into air intake port 8 and thence into ports 8^a to the furnace.

In Fig. 4 the arrows indicate the course of the hot gases or products of combustion and the air to be heated as they pass into the regenerators. It will be noted that the flames or hot gases are directed from the exhaust into the upper part of the regenerator chamber and travel down through the checkerwork, while the air to be heated is admitted into the lower part of the regenerator chamber and flows upwardly through the checkerwork. When the air to be heated is passed through the regenerator chamber, the heat previously absorbed by the checkers from the hot gases is partly expended in heating the air and in view of the fact that the relatively cold air when admitted into the regenerator chamber first contacts with the lower portion of the checkers, and also in view of the tendency of warm or hot air to rise, the upper part of the checkers and regenerator chamber will be much warmer than the lower part of the checkers and regenerator chamber during the portion of the cycle when the hot gases are directed into the regenerator. In other words, there is differential temperature head pressure set up in

the regenerators which will cause the hot gases to flow down through the checkers, or from the relatively warm to the relatively cool portion of the regenerator chambers, and conversely, this difference in temperature will cause the incoming cold air to flow upwardly through the checkers, or from the relatively cool to the relatively warm portion of the regenerator chambers, and this action is augmented by the exhaust pressure and flue draft. While it is preferred to build the checkerwork with graduated checker openings, as heretofore stated, and such construction is herein shown, yet due to the foregoing action, the regenerators will function in an efficient manner with any suitable arrangement of checkerwork, as in any event the hot gases and air to be heated will be equally and proportionally distributed throughout the checker passages.

The operation of the furnace will be readily understood by those having a knowledge of the art. The reversing valves may be automatically operated in proper order to alternately direct the waste gases or products of combustion into the regenerators 12 and 13. Assume that the instant order of the cycle is to direct the hot gases through the regenerator 12 and the air to be heated through regenerator 13. The valves 18, 24^a, 26^a and 20 would then be closed and valves 18^a, 24, 26 and 20^a opened, and the gases from the furnace would thus be directed into the regenerator 12 and closed off from 13 while the air would be admitted into regenerator 13 and closed off from 12. As heretofore stated, the hot gases pass into the dome or top part of the regenerator chamber and down through the checker work into the bottom part of the regenerator chamber and out through the port 19^a and flue 21 to the stack. The air would be admitted through inlet port 23 into the bottom part of the chamber of the regenerator 13 and passes up through the checkers and into the top part of the chamber of regenerator 13, thus becoming heated, and flows along said chamber and finally passes out through outlet passage 25 and into air intake 8 and upwardly through passage 8^a to be mixed with the fuel and the flame directed onto the bath.

While both the hot gases and air to be heated could be admitted into the lower part of the regenerator chambers as commonly practiced, yet it is preferred to have the air flow through the checkers in a direction counter to the flow of the gases or products of combustion, so that it passes from the coldest to the hottest portion of the checkers and thence to the furnace, and thereby improve the efficiency of the regenerators. The arrangement of the checkers as shown in the drawings is an example of a construction which has proved advantageous in regenerators, the larger openings being provided at

the inlet extremity, or where the hot gases are directed into the regenerators from the exhaust.

What is claimed as new is:

- 5 1. The combination with a furnace having unidirectional combustion, of a stationary horse-shoe shaped regenerator structure having inlet and discharge ports permanently connected to the exhaust and intake ports 10 of the furnace, and means for alternately directing the products of combustion and the air to be heated through the regenerator in the same direction.
- 15 2. The combination with an open hearth furnace provided with inlet and discharge ports, respectively, for fuel and products of combustion of a stationary horse-shoe shaped regenerator provided with a plurality of regenerator chambers in permanent communication at opposite extremities, with said inlet and discharge ports, and means for alternately directing the products of combustion from the furnace through the chambers of the regenerator.
- 20 3. In combination, an open hearth furnace having unidirectional combustion, of a plurality of stationary horse-shoe shaped regenerator chambers having inlet ports for waste gases permanently connected to the exhaust 25 ports of the furnace, and means for alternately diverting the said gases into said chambers.
- 30 4. In combination, an open hearth furnace having inlet and exhaust ports, of a plurality of horse-shoe shaped stationary regenerator chambers having inlet ports for waste gases at one extremity in alternate communication with the exhaust port of the furnace and additional ports at the same extremity 35 for alternate intake of air or both air and fuel.
- 40 5. In combination, an open hearth furnace having unidirectional combustion, of a plurality of horse-shoe shaped stationary regenerator chambers having inlet ports for the products of combustion and the air to be heated at one extremity and outlet ports leading to the discharge flues and air intake ports of the furnace at the other extremity, 45 and means for controlling alternate flow of the products of combustion and the air to be heated through said chambers.
- 50 6. The combination with an open hearth furnace provided with an inlet port at one end and a discharge port at the opposite end, said ports being, respectively, for fuel and products of combustion, of a stationary horse-shoe shaped regenerator provided with a plurality of regenerator chambers in permanent communication at opposite extremities with said inlet and discharge ports, said inlet and discharge ports communicating with said regenerator chambers adjacent the top thereof, said regenerator chambers being 55 provided with air inlet ports adjacent the

bottoms thereof and near their ends, which communicate with said furnace discharge port, and said regenerator chambers being provided with discharge ports adjacent the bottoms thereof near their ends which communicate with said furnace inlet port for the discharge of the products of combustion, and means for controlling the alternate flow of the products of combustion and the air to be heated through said chambers.

In witness whereof, I have hereunto set my hand.

LOUIS C. EDGAR.
